UNITED STATES PATENT OFFICE.

WINFORD P. LARSON, OF MINNEAPOLIS, MINNESOTA.

DENTIFRICE.

No Drawing.

Application filed September 28, 1925. Serial No. 59,234.

There are today a number of tooth pastes, tooth powders and mouth washes on the market which are claimed to be disinfectant and thus promote healthy gums and teeth. These all come under the general term of "dentifrices." It is impossible to use a disinfectant in the mouth of sufficient strength to destroy the bacteria there present without also injuring the tissues, and thus more harm than benefit may result from the use of such dentifrices.

In studying this problem, I have found that it is possible to render the mouth bacteria and their products,—commonly called toxins,—harmless by treating them with a properly prepared castor oil soap.

I have found that mouth bacteria, such as streptococci and pneumococci, are very sensitive to the action of a weak solution of castor oil soap. I have found that the bacteria mentioned, which are universally present in the mouths of human beings, lose their power to cause infection after being treated for one minute,—often less,—with a one per cent solution of castor oil soap.

I have found that the toxins produced by streptococci and certain other bacteria are instantly rendered non-toxic by treatment with castor oil soap.

The soap acts upon the bacteria and their poisons by being adsorbed onto their surfaces which renders them harmless. In preparing a tooth paste by my method I mix a solution of castor oil soap with an abrasive,—such as calcium carbonate,—together with a "binder" and flavoring material which makes it more palatable, in such proportions that some free soap is present when a quantity of the tooth paste is dissolved in a small quantity of fluid,—such as saliva,—when the paste is being used. This is of fundamental importance, since the castor oil soap will, as stated above, be adsorbed onto the surface of any particle with which it comes in contact. It is therefore necessary to satisfy all of the adsorptive requirements of the particles present, and still

have enough free soap present to affect the bacteria and their poisons when used in the mouth.

Applicant is aware of the fact that there are now several tooth pastes on the market which contain soap. In these tooth pastes soap is used only for its cleansing properties. I have examined all of these pastes and find that none either destroy the mouth bacteria or their toxins.

The reason castor oil soap acts differently from other soaps in this respect is the fact that castor oil contains practically no fatty acids other than ricinoleic acid, and therefore a castor oil soap is very soluble.

Ordinary soaps, on the other hand, contain large quantities of stearic and palmitic acids, whose soaps are insoluble in water at ordinary temperatures. The result is that these insoluble soaps adsorb onto their surfaces, the soluble ones, and the latter are not free to act upon bacteria and their toxins.

I claim as my invention:

1. A dentifrice containing castor oil soap.
2. A dentifrice comprising a suitable vehicle and castor oil soap mixed therewith.
3. A dentifrice containing the soap of an unsaturated fatty acid.
4. A dentifrice containing the soap of an unsaturated fatty acid mixed with abrasives and flavoring materials and capable when used of detoxifying bacterial toxins existing in the mouth of the user.
5. A dentifrice composed of a solution of the soap of an unsaturated fatty acid in a dental cream article forming a paste and capable when used of detoxifying bacterial toxins existing in the mouth of the user.
6. A dentifrice containing a solution of castor oil soap in a dental cream article forming a paste and capable when used of detoxifying bacterial toxins existing in the mouth of the user.

In witness whereof, I have hereunto set my hand this 25th day of September, 1925.

WINFORD P. LARSON.

Certificate of Correction.

Patent No. 1,633,336.

Granted June 21, 1927, to

WINFORD P. LARSON.

It is hereby certified that error appears in the printed specification of the above-numbered patent requiring correction as follows: Page 1, lines 43 and 44, for the word "absorbed" read *adsorbed*; and that the said Letters Patent should be read with this correction therein that the same may conform to the record of the case in the Patent Office.

Signed and sealed this 18th day of October, A. D. 1927.

[SEAL.]

M. J. MOORE,
Acting Commissioner of Patents.
